UNITED STATES PATENT OFFICE.

CHARLES W. FILLMORE, OF MARENGO, ILLINOIS.

HUB FOR VEHICLE-WHEELS.

SPECIFICATION forming part of Letters Patent No. 324,927, dated August 25, 1885.

Application filed June 11, 1885. (No model.)

To all whom it may concern :

Be known it that I, CHARLES W. FILLMORE, a resident of Marengo, in the county of McHenry and State of Illinois, have invented 5 certain new and useful Improvements in Vehicle-Hubs; and I do hereby declare the following to be a full, clear, and exact description of the invention, such as will enable others skilled in the art to which it pertains to make 10 and use the same.

My invention relates to improvements in hubs for vehicles, and is fully described and claimed in the following specification, and shown in the accompanying drawings, in 15 which—

Figure 1 is a plan of a hub with my improvements in place; Fig. 2, a central longitudinal section passing through two opposite spokes; Fig. 3, a section perpendicular to the axis of 20 the hub, through x y , Fig. 1, looking in the direction of the arrow a ; Fig. 4, a side elevation of the metallic retaining-bar E ; and Fig. 5, a section of E , made on the dotted line m , looking in the direction a' , Fig. 4.

In Fig. 1 A is the body of a wooden hub; B , a band of metal encircling it and in contact therewith; C , aperture in said band, corresponding in size and form to the cross-section of the larger part of an ordinary spoke, F ; ff are mortises for the reception of tenons F' , Fig. 3, on spokes F . e e' are shoulders on which the shoulders G G' , Fig. 3, of the spokes rest.

In Fig. 2 the metallic retaining bar E is 35 shown in longitudinal section sunken into the body of the hub A , its outer edge being flush with the outer surface of said hub. This figure also shows the opening H for the axis of the vehicle and the thickness of the band B , 40 as well as its position with reference to the retaining-bars E .

Fig. 3 is entirely in section and shows the parts A' A' of the hub lying between the spoke-tenons F' F' , which are all in place, the 45 bars E resting upon the outer surfaces of the portions A' A' of the hub, and held in close contact therewith by the band B ; also, the manner in which the retaining-bars E strengthen and support the spokes, being held 50 rigidly against their sides.

The bar E (shown detached in Figs. 4 and 5) is of the general width or thickness shown

in Fig. 5, but has upon each side, at a suitable distance from the end to allow the passage of the spoke, a gain or groove, I , between the shoulders e e' . When, as in Fig. 1, the spokes are not all in the same plane, these grooves on the two sides of the bar E are not exactly opposite, but, as shown in Fig. 5, where one gain or groove lies between e and e' , and the one on the opposite side between m and m' .

In forming this wheel the hub is mortised for the insertion of the metallic retaining-bars E , and the wood is further cut away to permit the larger part of the spoke to pass 65 inward to the shoulders e e' , and the tenon-mortise f is cut to the axial opening H , or to any desired depth. The bars E are then placed in position and the band B is forced over the hub, care being taken that its openings are made to coincide with the recesses in the hub. The spokes are then inserted and driven home, when, so far as the union of hub and spokes is concerned, the wheel is completed, the above-described parts being now 70 joined in such manner as to secure great strength and rigidity, combined with simplicity and cheapness of construction.

I am aware that wooden hubs with various metallic strengthening attachments have been 80 heretofore employed, and I do not therefore claim such construction, broadly; but

What I do claim as novel, and of the substance of my invention, is—

1. The combination, with a wooden hub 85 having a series of spoke-mortises adapted to receive the full-sized ends of a series of spokes and having a series of tenon-mortises extending inward from said spoke-mortises, of a series of metal retaining-plates flush with the 90 surface of the hub, lying between said spoke-mortises and forming the side walls thereof, and a single-piece band encircling said hub and retaining-plates and formed with openings for the admission of the spokes to said 95 spoke-mortises.

2. The combination, with a wooden hub having a series of spoke-mortises adapted to receive the full-sized ends of a series of spokes and having a series of tenon-mortises extending 100 inward from said spoke-mortises, of a series of metal retaining-plates flush with the surface of the hub, lying between said spoke-mortises and forming the side walls thereof,

and having their ends embedded in the wood of the hub on opposite sides of the line of said spoke-mortises, and a single-piece band encircling said hub and said retaining-plates, and formed with openings corresponding in size and position to said spoke-mortises.

3. The combination, with a wooden hub having a series of spoke-mortises and a series of tenon-mortises extending inward from said spoke-mortises, of a series of spokes whose tenons lie in said tenon-mortises and whose tenon-shoulders rest on the bottom of said spoke-mortises, a series of metal retaining-plates lying between the spokes and having their ends embedded in the wood of the hub on opposite sides of the plane of the spokes, and a single-piece metal band encircling the hub and the retaining-plates and formed with openings for the admission of the spokes.
- 20 4. The combination with a wooden hub having a series of spoke-mortises and a series of tenon-mortises extending inward from said spoke-mortises, of the metal retaining-plates E, shown and described, lying between said spoke-mortises, and the single-piece band B encircling said hub and retaining-plates and formed with openings for the admission of the spokes to the spoke-mortises, each of said retaining-plates being flush with the surface of

the wooden hub and consisting of a body 30 adapted to fill the space between two contiguous spokes, and two projecting ends of greater thickness than the body and embedded in the wood of the hub on opposite sides of the line of mortises.

5. The combination, with the hub A, having a series of spoke-mortises and a series of tenon-mortises extending inward from said spoke-mortises, of the retaining-plates E, lying between said spoke-mortises and having their 40 ends embedded in the wood of the hub on opposite sides of the line of mortises of the single-piece band B encircling said hub and retaining-plates, and having openings corresponding to the spoke-mortises, each of said 45 retaining-plates having in its opposite faces the gains or grooves I, to permit the admission of spokes to the spoke-mortises, substantially as shown and described, and for the purpose set forth.
- 50 In testimony whereof I have signed this specification in the presence of two subscribing witnesses.

CHARLES W. FILLMORE.
